UNITED STATES PATENT OFFICE.

AVEDIS S. KHANZADIAN, OF BINGHAMTON, NEW YORK.

RUG-CLEANING MACHINE.

Application filed February 11, 1926. Serial No. 87,602.

My invention relates to washing and scrubbing machines and particularly to that type adapted for the cleansing of rugs.

The primary object of my invention is to provide a machine so designed as to simulate as nearly as possible the motions and operations usually employed in washing rugs by the slow and more tedious hand method.

Another object is to provide such a machine which is adapted to reciprocate back and forth over the surface of the rug or other articles to be cleaned, and which is provided with power driving means both for the reciprocating part and the scrubbing element.

A further object is to provide means for adjusting the pressure of the scrubbing and scraping or wringing elements downwardly against the surface of the rug.

20 A still further object is to provide novel means for rinsing during the scrubbing operation and for immediately and automatically pressing the rinse water from the surface of the rug.

25 Another object is the provision of a novel soap container for feeding the scrubbing brush with a cleansing solution.

A further object is to provide a carriage mechanism with driving means therefor which is driven from the same source as is the scrubbing element and which renders the machine practically automatic in its operation, thus reducing to a minimum the hand work required in the washing of a rug.

35 A still further object is to provide an inclined supporting bed and suitable tracks over and upon which the carriage carrying the washing apparatus may travel.

40 Means are also provided for the proper drainage of the used cleaning solutions.

One further object is to provide means in conjunction with the scraping or wringing device which will immediately precede its operation and tend to iron out the wrinkles and irregularities in the rug.

45 Other objects and advantages in details of construction and operation will be apparent as the description proceeds, reference being had to the accompanying drawings wherein like reference numerals indicate like parts.

In the drawings:—

Figure 1 is a perspective view of the assembled machine.

Figure 2 is a detail perspective view of 55 a part of the carriage and illustrating clearly the scraping device and the means for adjusting the same.

Figure 3 is a detail end view of the machine partly in section and with certain parts omitted to illustrate clearly the driving means for the carriage.

Figure 4 is a detail side view illustrating 60 part of the driving mechanism and scrubbing element.

Figure 5 is a detail cross section of the scrubber and illustrating clearly the rinsing means.

Figure 6 is a detail cross section of a 65 modified form of rail or support for the carriage.

Figure 7 is a detail side view of the same.

Figure 8 is a side view, partly in section, of the assembled relation of certain parts of 70 the machine.

The reference numeral 1 indicates an inclined platform or supporting bed preferably of concrete or other suitable material, having a perfectly smooth surface 2, which slopes downwardly from one end. Drain 75 troughs 3 are provided adjacent each edge of the platform to receive and carry off the used washing solution and rinse water.

At the upper end of the platform 1 and at each side thereof are placed wooden supporting blocks 4 suitably secured to the concrete base and provided with drain troughs 5 in alignment with the troughs 3 of the platform. At a point adjacent the lower end of the platform similar blocks 6 are also inserted and are similarly provided with the aligned drain troughs 7. The blocks 4 and 6 have been specified as being of wood, but it will be understood that this is the preferred material only, and other suitable materials may be used. Such construction renders it comparatively easy to assemble or dismantle the machine on its platform without destroying the platform. These blocks are adapted to support the four upright posts 8, bolted or otherwise secured rigidly to the blocks as at 9. Rail members 10 connect the posts 8 on the same side of the platform and directly above these rails are additional rail members 11 also running longitudinal of the platform and securely mounted between the posts 8. These rails just described form a track and

100

105

support for the reciprocating carriage to be described. As shown clearly in Figure 1, the lower edges of the upper rails 11 are provided with teeth 12 for a purpose to be 5 described.

Mounted upon either side of the rails 10 and 11 are vertical supporting plates 13. Each set of plates is connected together by means of pins 14 extending laterally between 10 the rails 10 and 11, and the pins 15 extending laterally beneath the lower rail 10. Ears 16 are formed upwardly from the upper edges of the plates 13 and pins 17 also connect the plate 13 through such ears above 15 the upper rail 11. Rotatably mounted upon the pins 14, 15 and 17 are grooved rollers 18, (see Figure 3) embracing and riding, upon the bevelled upper and lower edges of the rails 10 and the upper bevelled edges of 20 rails 11. It will thus be seen that each set of plates 13 provides a slidably supporting means movable back and forth upon the rails 10 and 11.

These sets of plates are rigidly connected 25 primarily by a channeled cross piece 19, shown clearly in Figure 2, and connected at each end with the inner plate 13 on either side of the platform. One of the outer plates 13, as shown clearly in Figure 1, is 30 provided with an outwardly extending horizontal platform 20 upon which is mounted an electric motor or other source of power 21. The shaft 22 of this motor projects inwardly over the top of rail 11 35 and beyond the inner face of the adjacent inside plate 13. A pinion 23 is secured upon the end of this shaft and a driving chain 24 connects this pinion with the gear 25 mounted upon a shaft 26 extending between the 40 two inside plates 13 and having suitable bearing therein. A second gear 27 is also carried by this shaft 26 adjacent the gear 25 and is rotatable therewith. Meshing with the gear 27 is a gear 28 secured to shaft 29 45 also extending between the inside plates 13 and having suitable bearing therein. Also rigid with the shaft 29 and positioned between the plates 13 as shown clearly in Figure 3, is a pinion 30 having engagement 50 with the teeth 12 of the rail 11. The opposite end of the shaft 26 also carries a gear 27^a which meshes with the gear 28^a carried at this end of the shaft 29. The pinion 30^a is also carried at this end of the shaft 29 55 between the plates 13 and meshes with the adjacent teeth 12 of the rail 11.

From the foregoing, it will be understood that upon operation of the motor 21, the shaft 26 will be rotated and such motion 60 imparted to shaft 29 through the gears 27 and 28. The pinions 30 and 30^a being rigid with the shaft 29 and engaging with the teeth 12 of the rails 11 will cause the carriage comprising the plates 13 and the various connections just described between

such plates, to travel along the rails. It will be understood that by reversing the direction of the motor, the carriage may be made to travel back and forth in this manner. It will also be understood that the 70 gear ratio between the various gears just described will in practice be such as to impart a slow movement to the carriage.

Pivoted upon the shafts 26 between the gears 25 and 27 on the one side and just inside the gear 27^a on the opposite side of the carriage, are arms 31 supporting at their lower ends a shaft 32 (see Figure 4) upon which is secured a brush or other scrub element 33. Each end of this shaft 32 is provided with a pinion 34 meshing with the gears 27 and 27^a respectively. As the pinions 34 are comparatively small with respect to the gears 27 and 27^a, it will be understood that the rotation of the brush 33 80 will be comparatively fast in relation to the movement of the carriage.

Also suitably supported by the pivoted arms 31 is a semi-circular splash guard 35 extending over the upper portion of the 90 brush 33 whereby to prevent the washing solution to be thrown upwardly from the brush. This splash guard 35 extends lengthwise between the pivoted arms 31, and on its upper side supports a V-shaped hopper or soap container 36 preferably divided into compartments 37 into which the soap or cleaning solution may be placed and fed through the bottom of the hopper and through an opening 37 in the upper surface 100 of the splash guard 35 on to the rotatable brush 33. It will be understood that if a rug narrower than the width of the platform 1 is to be washed, it will be necessary to fill only so many of the compartments 37 of the hopper as will adequately cover the rug. If desired, some suitable form of regulating means for the hopper 36 may be provided for adjusting the amount of flow 110 therefrom on to the brush.

As illustrated clearly in Figure 2, the channeled cross piece 19 extending between the inside plates 13 is provided adjacent each end with rigid upstanding pins 38. A second set of upstanding pins 39, also rigid 115 with the top of the cross piece 19 are positioned just inside the pins 38 and to the top of these pins 39 is secured rigidly a fixed bracket 40, as by bolts or screws 41. A wringing or scraping device hereinafter 120 called a scraper and indicated at 42 is made in channeled form to fit downwardly over the cross piece 19 and is provided with suitable openings 43 through which the pins 39 may pass and with upstanding sleeves 44 125 encircling the pins 38, whereby lateral movement of the scraper 42 with relation to the cross piece 19 is prevented. The downwardly extending sides of the scraper 42 are flared outwardly as at 45 and the lower 130

edges thereof cut parallel with the platform 2. The upper side of the scraper 42 is provided with upstanding ears or lugs 46 forming bearings for the pintles 47 to which are secured the ends of a leaf spring 48 which as shown may constitute one or more leaves bowed upwardly to provide tension. The bracket 40 is provided centrally thereof and directly over the center of the spring 48 with an upstanding screw threaded bearing 49 through which is threaded an adjusting screw 50 secured at its lower end in any suitable manner to the spring 48. A suitable hand wheel or grip 51 is secured to the upper end of the adjusting screw 50.

From the foregoing, it will be understood that if the adjusting screw 50 is turned to the right in Figure 2, the spring 48 will be pressed downwardly under tension, resulting in the resilient forcing downwardly of the scraper 42. Conversely, if the screw 50 is turned in the opposite direction, the scraper 42 may be raised with relation to the cross piece 19.

The bracket 40 is provided centrally with a forwardly extending arm 52 through the front end of which is suitably threaded an adjusting screw 53 provided with a hand wheel or grip 54 and secured at its lower end to a pin 55, (see Figure 1), rotatably mounted in upstanding ears or bearings 56 on the splash guard 35. By this means, it will be apparent that upon adjustment of the screw 53, the brush 33, splash guard 35 and soap container 36 may be raised or lowered as desired. In such event, the arms 31 supporting these elements just named will be rocked on their pivots upon the shaft 26 and the pinions 34 will ride upwardly upon the teeth of the gears 27 and 27^a. The swivel connection between the lower end of the adjusting screw 53 and the top of the splash guard 35 permits such pivotal movement.

A suitable source of water supply may be provided adjacent the machine and connecting therewith by the flexible hose 57. The lower end of the hose 57 is connected to a pipe 58 suitably supported on one of the plates 13 as at 59 and provided with the controlling valve 60. As shown clearly in Figure 5, the lower end of the pipe 58 opens into the horizontal pipe section 61 extending across the carriage within the channeled cross piece 19. This pipe 61 is provided with suitable spaced openings through which the water 61^a may be forced out on to the surface of the rug. Just above the cross piece 19 and the scraper 42, pipe 58 is provided with a T coupling 62 whereby some of the water may be diverted from pipe 58 forwardly and downwardly just ahead of the scraper 42, through the pipe section 63 into the horizontal pipe 64 running across the carriage just in front of the scraper 42.

This pipe 64 is also provided with openings through which the water may be forced downwardly into the path of the scraper. This arrangement permits a double rinsing operation after the scrubbed operation of the brush. The lower edges of the scraper 42 when pressed into close contact with the rug act to press the water ahead as the carriage moves over the rug and off on to the platform 2 where it drains into a suitable sewer or receptacle.

As illustrated in Figure 5, if desired the front outwardly turned side 45 of the scraper 42 may carry at each end a bracket 65 on the free ends of which may be journaled a roller 66 which precedes this scraper in its movement in one direction and acts to roll out the wrinkles which may appear in the rug.

In Figures 6 and 7, I have shown a modified form of rail construction which comprises an upper rail 67 provided with teeth 68 on its under side for engagement with the pinion 30 carried on the end of the shaft 29, and a lower rail 68 of channel form, that is, provided with the inturned flanges 69 and 70. The adjacent plate 71 forming one end of the carriage is provided with pins 72 carrying rollers 73 engaging the upper and lower flanges 69 and 70 on the inside thereof. The plate 71 is also provided with suitable openings 74 across which are mounted vertical pins 75 carrying the horizontal rollers 76 engageable with the inner face of the side of the channeled rail 68. This roller arrangement provides a protective guiding means and traveling mechanism for the carriage. In this case, the gear 28 meshes with the gears 27 as before, which in turn, meshes with an intermediate gear 77 which drives the brush pinion 34. The pivoted arm 78 mounted on the shaft 26 corresponds to the arm 31 of Figures 1 and 3.

It will be understood that similar rail construction is provided on each side of the platform as in the modification first described, and as the parts on each side are practically the same, a duplication is believed to be unnecessary, and one side only has therefore been shown.

The operation of my invention is as follows:—

When it is desired to wash or clean a rug, the operator first operates the adjusting screws 50 and 53 to raise the scraper 42 and brush 33 above the platform surface 2. The rug is then spread flat upon the platform and secured in any suitable manner thereto. The adjusting screws are again operated to force the brush and the scraper downwardly into engagement with the upper surface of the rug, the water turned on through the pipes heretofore described and the soap solution or other cleaning material fed from the compartments 37 on to the brush 33. The

motor now being started rapidly revolves the brush 33 and slowly moves the carriage along the rails 10 and 11. By reversing the direction of the motor 21, the carriage may be moved back and forth across the rug as many times as desired. It will be observed that directly following the scrubbing operation of the brush, the roller 66 engages the rug and rolls the surplus cleaning solution ahead of the scraper 42 and also water from the pipe 64 is forced on to the rug just in front of one side of the scraper. The movement of the scraper across the rug, resiliently forced downwardly by the adjusting means above described, pushes the rinse water ahead where it may run off of the rug and drain from the platform through the troughs 3. A second rinsing operation occurs between the edges of the scraper 42 by means of the pipe 63 forcing fresh clean water on to the rug just in front of the rear side of the scraper 42.

The action of the scraper 42 on the rug very closely simulates the action of the hand 25 of an operator scrubbing and rinsing a rug by the hand method. Pressure is exerted downwardly and forwardly as the carriage moves along the rails.

Many changes in details of construction 30 and operation may be made without departing from the scope of my invention. I do not limit myself therefore to the exact form shown other than by the appended claims.

I claim:

35 1. A rug cleaning machine comprising an inclined rug supporting platform, supporting blocks in said platform, posts secured to said blocks, rails mounted on said posts, a carriage movable on said rails, and rug 40 washing mechanism on said carriage adapted for engagement with a rug on said platform.

2. A rug cleaning machine comprising an inclined rug supporting platform, upstanding posts thereon supporting rails mounted 45 on said posts longitudinally of said platform and parallel therewith, a movable carriage on said rails comprising spaced plates provided with rollers engaging said rails, and rug washing mechanism carried between 50 said plates and adapted for engagement with a rug on said platform.

3. A rug cleaning machine comprising a platform, supporting rails mounted on 55 parallel sides of the platform, each comprising two spaced track members, one above the other, a movable carriage on said rails comprising spaced plates on each side of said rails and provided with rollers engaging the upper and lower edges of said track 60 members, and rug cleaning mechanism carried by said plates.

4. A rug cleaning machine comprising a platform, supporting rails mounted on 65 parallel sides of the platform each comprising

ing two spaced track members one above the other, a movable carriage on said rails comprising spaced plates on each side of each rail and having rollers between said spaced plates and engaging the upper and 70 lower edges of said track members, and rug cleaning mechanism carried by said carriage over said platform.

5. A rug cleaning machine comprising an inclined rug supporting platform, supporting rails mounted thereon and parallel therewith including track members, teeth on said track members, a movable carriage on said rails, a motor on said carriage, driving gear connections between said motor and said 75 teeth for moving said carriage on said rails, rug washing mechanism on said carriage for engagement with a rug on said platform, and means connecting said motor and said mechanism for operating said mechanism.

6. A rug cleaning machine comprising a rug supporting platform, supporting rails mounted thereon, a carriage movable on said rails over said platform, a rotatable scrubbing element pivoted to said carriage and 90 adjustable on its pivot toward and away from said platform.

7. A rug cleaning machine comprising a platform, supporting rails thereon, a movable carriage on said rails, a rotatable scrubbing element on said carriage above said 95 platform, a splash guard for said element and a soap container on said guard.

8. A rug cleaning machine comprising a platform, supporting rails thereon, a movable carriage on said rails, a rotatable scrubbing element on said carriage above said platform, a splash guard for said element and a soap container on said guard, said 100 scrubbing element, splash guard and soap container being adjustable toward and away from said platform.

9. A rug cleaning machine comprising a platform, supporting rails thereon, a movable carriage on said rails, a rotatable scrubbing element on said carriage above said platform, a splash guard for said element and a soap container on said guard, said scrubbing element, splash guard and soap 105 container being adjustable toward and away from said platform, and a single adjusting means for all of said members.

10. A rug cleaning machine comprising a platform, supporting rails thereon, a movable carriage on said rails, a rotatable scrubbing element on said carriage, a splash guard for said element, a soap container on said guard divided into compartments and adapted to feed soap onto said scrubbing element through an opening in the wall of 110 said guard.

11. A rug cleaning machine comprising a platform, supporting rails thereon, a movable carriage on said rails, pivoted arms on said carriage, a rotatable scrubbing element, 115

a splash guard and soap container mounted on said arms over said platform, and means for adjusting said arms toward and away from said platform.

5 12. A rug cleaning machine comprising a platform, supporting rails thereon, a movable carriage on said rails, pivoted arms on said carriage, a rotatable scrubbing element, a splash guard and soap container mounted 10 on said arms over said platform, and means for adjusting said arms toward and away from said platform, a motor on said carriage, a pinion on said scrubbing element and driving connections between said motor 15 and said pinion.

13. A rug cleaning machine comprising a platform, supporting rails thereon, a movable carriage on said rails, pivoted arms on said carriage, a rotatable scrubbing element, 20 a splash guard and soap container mounted on said arms over said platform, and means for adjusting said arms toward and away from said platform, a motor on said carriage, a pinion on said scrubbing element 25 and driving connections between said motor and said pinion, said driving means including means for moving said carriage on said rails.

14. A rug cleaning machine comprising a 30 platform, supporting rails thereon, a movable carriage on said rails, a rotatable scrubbing element on said carriage, a scraper on said carriage adjacent said scrubbing element, and means for independently adjusting said scrubbing element and said scraper toward and away from said platform.

15. A rug cleaning machine comprising a platform, supporting rails thereon, a carriage movable on said rails over said platform, a scrubbing element on said carriage, a scraper on said carriage adjacent said scrubbing element comprising a channeled member provided with flared sides adjustable toward and away from said platform.

40 16. A rug cleaning machine comprising a platform, supporting rails thereon, a carriage movable on said rails over said platform, a scrubbing element on said carriage, a scraper on said carriage adjacent to and 45 parallel with said scrubbing element, said scraper comprising a channeled member provided with flared sides, and a water spray

between said scrubbing element and said scraper.

17. A rug cleaning machine comprising a 50 platform, supporting rails thereon, a carriage movable on said rails over said platform, a scrubbing element on said carriage, a scraper on said carriage adjacent to and parallel with said scrubbing element, said 55 scraper comprising a channeled member provided with flared sides, and a water spray between said scrubbing element and said scraper, and a second water spray within the channel of said scraper. 65

18. A rug cleaning machine comprising a platform, supporting rails thereon, a carriage movable on said rails over said platform, a scrubbing element on said carriage, a scraper on said carriage adjacent to and 70 parallel with said scrubbing element, said scraper comprising a channeled member provided with flared sides, and a water spray between said scrubbing element and said 75 scraper, and a second water spray within the channel of said scraper, the edges of the flared sides of said scraper being parallel with said platform, and means for adjusting said scraper toward and away from said platform. 80

19. A rug cleaning machine comprising an inclined platform, supporting rails thereon and parallel therewith, a movable carriage on said rails, a rotatable scrubbing element on said carriage, a splash guard and a 85 soap container for said scrubbing element, said element, guard, and container being adjustable as a unit toward and away from said platform, a scraper in said carriage adjacent said scrubbing element and parallel 90 thereto, and a double rinsing means in combination with said scraper.

20. A rug cleaning machine comprising an inclined platform, drainage troughs therein, supporting rails thereon and parallel therewith, a movable carriage on said rails, a scrubbing element on said carriage, means for feeding a cleaning solution on to said scrubbing element, means for rinsing with water following said scrubbing element, and a scraper for forcing the used cleaning solution and rinse water into said drainage troughs. 95 100

AVEDIS S. KHANZADIAN.
